UNITED STATES PATENT OFFICE.

ISIDRO RODRIGUEZ ZARRACINA, OF VALLADOLID, SPAIN.

CARBURETOR FOR INTERNAL-COMBUSTION ENGINES.

Application filed April 9, 1925, Serial No. 21,890, and in Great Britain December 10, 1924.

It is well known that in aviation motors the considerable variations in the fuel feed due to changes in altitude which result in corresponding variations in the proportions 5 of the combustible mixture supplied to the engine, and that with any ordinary carburetor not provided with a device to annul or compensate such variations, the motor works irregularly, is deficient in power or 10 extravagant in the consumption of fuel.

The primary object of the present invention is to provide a carburetor for aviation motors with means whereby the proper proportions of the constituents of the combustible mixture can be maintained with changes 15 of altitude, but the invention is not restricted to aviation motors, and can also be applied usefully to land or marine internal combustion engines which are over-compressed or 20 over-charged and are liable to show irregularities in working.

According to the present invention constancy in the proportions of the fuel mixture is maintained for different altitudes by means 25 of a valve device whereby the supply of air to the primary mixing chamber of the carburetor and the pressure on the float chamber or other constant level fuel reservoir are conjointly varied. Further, this valve is so 30 designed that while rotation in one direction through a varying angle effects the necessary compensation for different altitudes at moderate heights of flight, rotation in the reverse direction provides similar compensation 35 over a zone of comparatively great altitudes, and to enable the pilot to make the appropriate adjustment of the valve mechanically in either zone the lever can be arranged to be shifted from one position to another 40 with respect to the valve spindle, so that the direction of movement of the valve lever to compensate for increasing altitude in either zone will be the same for both zones, say from left to right, and similarly for decreasing 45 altitude.

The invention will be more particularly described with reference to carburetors of the type described in the specifications of British Patents Nos. 127579, 153506 and 50 202472 granted to the present applicant, but it can be applied with suitable modifications to any ordinary carburetor.

In the accompanying drawings, which are merely diagrammatic, Fig. 1 represents a vertical section of a carburetor embodying the 55 invention, and Figs. 2, 3, 4, 5, 6 and 7 repre-

sent different working positions of the manually operated control valve.

As shown in Fig. 1, A is the engine throttle, B the main air inlet and C the main mixing chamber. A tube D, leads from the main air supply to a passage E controlled by a valve F and thence to a pipe G opening into the primary mixing chamber H. The valve F also controls a passage I leading to the 60 interior of the fuel reservoir J the level of which is maintained constant by suitable means, such as the usual float feed, and which supplies the main fuel orifice K. The idling or slow speed nozzle L is provided in a tube M 65 arranged concentrically within the primary air supply pipe G and depending into the primary mixing chamber. A pipe N bypasses the valve F and connects the primary air tube D with the tube M at a point beyond 70 the slow speed nozzle L and thence with passages O, P leading to the main mixing chamber C on opposite sides of the throttle A. The inlet end of passage P which leads to the engine side of the throttle is controlled by 75 suitable means, such as a screw valve Q. The primary mixing chamber leads to a perforated diffusion tube R which extends transversely across the main air supply passage B.

For low speed operation, the throttle A 80 is closed as shown in Fig. 1, leaving the adjustable passage P open to the engine intake. The suction of the motor induces a flow of air through pipes D, N, M and passage O to 85 passage P, and also draws liquid fuel from the chamber H through pipe M to feed the nozzle L.

When the throttle is opened the chamber H 90 becomes subject to the suction of the motor through the perforated diffusion pipe R. 95 During acceleration the chamber H is emptied of fuel and thereafter the fuel from the tank J issuing through the orifice K mixes with the air supplied through tube G, forming an emulsion rich in liquid fuel. There is a 100 second admixture of air with this emulsion within the diffusion tube R and a further admixture of air when the fuel mixture emerges from the tube R.

The operation of the engine produces a high 105 velocity of air entering the intake B and this pressure applied to the face of the tube R next the open end of the intake causes some of the air to enter and pass through the tube as the opposite face of this tube is subjected 110 to suction which effects a reduced pressure. This results in a suction within the tube R

and consequent feed of fuel from the chamber H which after its emission from the tube is further mixed with air at the portion C of the intake next the throttle.

6 With such a carburetor duly dimensioned for a given type of motor, the latter would be supplied with a mixture of definite proportions so long as the altitude remains unchanged, and this definite proportion can be 10 maintained at different altitudes provided the influx of air to the primary mixing chamber and the pressure in the fuel reservoir can be quickly and appropriately varied, and this is what is sought to be done by the present invention in the simplest and most efficacious manner by means of the valve F which controls the air supply through pipe G to the primary mixing chamber H and also, through duct I, the pressure on the surface of the fuel 15 in tank J.

The valve F, as shown in the drawings, is of the character of a ported rotary sleeve valve having two solid or obturating parts F', F² mounted in the interspace between two fixed 25 ported sleeves S, T, which are interposed between the pipes E, G, and I, as shown in Fig. 1. The obturator portion F² has a radial port F³ of small cross section.

The rotary valve is actuated by means of 30 a lever U secured to the valve spindle in such a manner that it can be readily shifted from one angular position with respect to the spindle, for example that shown in Figs. 2, 3 and 4, to another angular position such as shown 35 in Figs. 5, 6 and 7. For one zone of altitudes the lever is secured on the spindle in the first position and for a higher zone of altitudes it is removed from its position in Figure 2 and applied in the second position of Figure 40 5, the object being to preserve the same direction of movement of the lever to compensate for increasing altitudes in both zones.

For ordinary flying altitudes in which it is not necessary to provide a great range of 45 compensation, the lever is fixed in the position shown in Figs. 2 to 4 and as the altitude increases it is shifted towards the right from the position of Fig. 2 through intermediate positions to the position shown in Fig. 4.

50 With the valve in the position shown in Fig. 2 the obturator F² blocks the inlet of the tube G with the exception of the aperture F³ which is provided to facilitate acceleration, whilst the primary air supply tube E and the passage I leading to the constant level fuel reservoir J are left open, with the result that the fuel surface is subjected to the same pressure as the main air inlet B of the carburetor. This is the position of the valve when the motor 55 is working on the ground level or without correction. As the valve is rotated towards the position of Fig. 3 the obturator F² begins to uncover the inlet of tube G so as to permit the air to pass more freely through 60 the tube G into the primary mixing chamber

H and thus restrain the flow of fuel through the main orifice K, the tubes E, and I being left fully open in the position of Fig. 3. When the valve is moved to the position of Fig. 4 the passages E and G are left fully 70 open, while the passage I leading to the fuel tank is closed but for the aperture F³, thus reducing the pressure on the surface of the fuel in the tank. This is the position of maximum correction for the first zone of comparatively low altitudes. 75

It will be seen that in the first of these three positions the supply of air to the primary mixing chamber is restricted to a maximum degree, while the effective pressure of the fuel in the main orifice K is a maximum. In position Fig. 3 the supply of air to the primary mixing chamber is increased, and the effective pressure of the main fuel orifice is reduced, and in the third position (Fig. 4) 80 the supply of air to the primary mixing chamber H is still further increased and the effective pressure in the orifice K is still further reduced. 85

When the lever U is set to the working 90 position for the zone of high altitudes and the valve is rotated in the opposite direction by the pilot moving the lever in the same absolute direction as before, the outlet of pipe E is 95 reduced, while the inlet of pipe G is opened, as shown in Fig. 6, and consequently the effective pressure in the main orifice K is reduced on both accounts, while the air supply to the primary mixing chamber is increased. When this movement of the valve is continued to the 100 position shown in Fig. 7, the pipe E is entirely blocked by the obturator F², whilst the pipes G and I remain open, with the result that the effective pressure in the main orifice K is nil and maximum compensation obtained, as no mixture will be under pressure 105 to K.

Whatever position of the valve, even in the position shown in Fig. 7, there is no interference with the operation of the slow running jet, so that the motor can always rotate with reduced admission or opening of the control valve. 110

With the parts in the position stated there is no direct air feed to the reservoir chamber and during slow speed running the air is fed by the by-pass N into the tube M which receives its fuel from the chamber H, and there is air admitted from the tube R when the throttle valve is closed. Under these conditions there is a feed of fuel by gravity 115 from the reservoir J to the primary mixing chamber H. 120

While the invention has been described with reference to its use with aviation motors, it can also be applied beneficially to supercharged surface motors, such as high speed racing motors. 125

Having now particularly described and ascertained the nature of my said invention and 130

in what manner the same is to be performed, I declare that what I claim is:—

1. In a carburetor, the combination with a fuel reservoir and a primary mixing chamber having a liquid fuel feed from the reservoir, of an air intake communicating with said reservoir and chamber, means for conjointly regulating the intake of air by separate connections to the reservoir and chamber, a feed tube carrying a body of liquid fuel, of an air intake, a conduit extending therefrom and having separate connections with said reservoir and chamber, a rotary valve disposed in said conduit to conjointly control the air pressure in said connections to the reservoir and chamber, a throttle valve in said intake, and a feed tube disposed in the intake and communicating with said chamber. 45
2. In a carburetor, the combination with a fuel reservoir and a primary mixing chamber having a liquid fuel feed from the reservoir, of an air intake communicating with said reservoir and chamber, means for conjointly regulating the intake of air by separate connections to the reservoir and chamber, and a perforated tube communicating with said chamber and extended across the air intake to receive the pressure therein upon its perforated face next the open end of the intake, whereby a fuel feed from the chamber and opposite face of the tube to the intake is effected. 50
3. In a carburetor, the combination with a fuel reservoir and a primary mixing chamber having a liquid fuel feed from the reservoir, of an air intake, a conduit extending therefrom and having separate connections with said reservoir and chamber, and a rotary valve disposed in said conduit to conjointly control the air pressure in the reservoir and chamber, 55 said valve being operable in one direction for one zone of operation and in an opposite direction for a different zone of operation. 60
4. In a carburetor, the combination with a fuel reservoir and a primary mixing chamber carrying a body of liquid fuel, of an air intake, a conduit extending therefrom and having separate connections with said reservoir and chamber, a rotary valve disposed in said conduit to conjointly control the air pressure in said connections to the reservoir and chamber, a throttle valve in said intake, a feed tube disposed in the intake and communicating with said chamber, a feed connection extending from said chamber to a position at the intake side of the throttle valve, and a bypass connection from the air conduit to the last named feed connection. 65
5. In a carburetor, the combination with a fuel reservoir and a primary mixing chamber, of an air intake, a conduit extending therefrom and communicating with said reservoir and chamber, and a rotary valve disposed in said conduit to conjointly control the air pressure in the reservoir and chamber, 70 said valve being operable in one direction for one zone of operation and in an opposite direction for a different zone of operation. 75
6. An apparatus as defined in claim 3 wherein the control valve is provided with an operating handle shiftable from one angular position upon the valve spindle to another angular position so that the adjusting movement of the lever for either range of adjustment will be in the same direction. 80
7. An apparatus as defined in claim 3 wherein the control valve is provided with an operating handle shiftable from one angular position upon the valve spindle to another angular position so that the adjusting movement of the lever for either range of adjustment will be in the same direction. 85

In testimony whereof I have signed my name to this specification.

ISIDRO RODRIGUEZ ZARRACINA.
